UNITED STATES PATENT OFFICE.

CHARLES D. WHITE, OF NORWICH, CONNECTICUT.

THREAD-GUARD AND SPINNING-RING HOLDER.

Application filed May 18, 1927. Serial No. 192,296.

This invention relates to ring spinning frames, and embodies certain improvements upon the combined thread guard and spinning ring holder described and claimed in 5 U. S. Patent No. 1,489,910, granted to me on April 8, 1924.

The invention as disclosed in said prior Letters Patent comprised a combined spinning ring holder and protecting device, the 10 latter being applied to each ring of a spinning frame, and constructed and arranged to extend partly but not wholly around the circumference of each ring so as to guard the ring and traveler from flying lint, 15 small particles of thread, etc., thrown off from adjacent rings. As shown in said patent, the spinning ring frame was provided at spaced intervals with openings to receive the bobbins, with recesses surrounding 20 said openings of a size and shape to receive the base flanges of the spinning rings while a longitudinal strip having cutout portions 25 therein corresponding to the openings in the rail was provided with overhanging flanges of a size and shape to partly surround each 30 ring, the flange extending in a curve about the ring for a little more than one-half the circumference of the ring, and said flange overlying, and being substantially coincident in its arc of curvature with the outside 35 diameter of the upper flange of the ring.

The flange afforded a protection to the ring and traveler, and furthermore was located in such proximity to the traveler as to prevent bowing of the yarn, and hold the same within a prescribed path of the traveler. Under the arrangement as shown in 40 said prior patent the number of bobbins which could be placed upon a rail of given length was determined by the spaces due to the width or distance between the edges of the adjacent flanges of the protector, measured longitudinally of the ring rail, as it is 45 not practical to locate adjacent rings any closer together than a distance which will prevent the yarn from adjacent bobbins from contacting with each other during the spinning operation.

I have discovered that with the construction as shown in my prior patent, if the flanges of the protector strip which overlie the rings in the several openings of the frame are increased in width so as to have

their inner edges substantially coincident 55 with the inner circle of the ring flange, the spacing between adjacent rings will be increased to such an extent as to permit the use of a greater number of rings on the same frame than would be possible under 60 the former construction; or, will permit the use of rings of a larger diameter than formerly, without decreasing the space between adjacent bobbin centers, or in other words, between adjacent spinning rings. Another 65 advantage following from the foregoing is that the overhanging flange will cause the yarn to be thrown toward the center of the ring with the result that the strain upon the traveler instead of being outwardly, will be 70 substantially equalized upon the outer and inner edges of the upper flange of the ring.

The foregoing and other advantages of the invention will be better understood from the following description, in connection with 75 the accompanying drawings and the claims appended hereto will point out the novel features of the invention.

Fig. 1 is a plan view of a portion of a spinning frame, showing three rings applied 80 thereto, and illustrating the present invention;

Fig. 2 is a front elevation of Fig. 1;

Fig. 3 is a section on line 3—3, Fig. 1; and

Fig. 4 is a section on the line 4—4, Fig. 1.

The rail 2 of a ring spinning frame is provided at suitable intervals with the usual openings 3 to receive the bobbins. As herein shown, a recess 5 is formed in the rail surrounding each opening to receive the base flange of a spinning ring 6, which spinning ring may be as shown herein of the double flange type, the upper flange or raceway being adapted to receive the usual traveler 7. The space between the flange 8 and the bead 9 on the ring constitutes the raceway for the traveler 7.

Sustained upon the rail 2, and secured thereto by screws 10, or other fastenings is a strip 16 having an appropriate number of cutout portions corresponding with the number of openings 3 on the rail above which the rings are supported. The strip is recessed at 12 to provide a clear space about each ring, the recesses being curved about the rings for more than one-half of a circle, and terminating in the openings at the front

of the strip, and said recesses are provided with overhanging flanges 14 which agree in curvature with the curvature of the recesses, and overhang the rings as shown especially in Fig. 3, the edge of each flange 14 being located immediately above and agreeing in curvature with, the inner edge of the upper flange of the ring. In my prior patent previously referred to the overlying flange 18 therein had its inner edge substantially coincident with the outer edge of the ring, whereby the yarn in passing about the edge of the flange was caused to pull the traveler outwardly, thereby throwing the entire wear 10 from the frictional engagement between the traveler and ring, upon the inner edge or portion of the traveler. This was found to be objectionable because it caused the traveler to wear out rapidly, as compared with the case in which the strain was equally divided between the outer and inner portions of the traveler which bear upon the outer and inner edges of the ring flange. Under the present invention the yarn is thrown inwardly by the flange 14 so as to exert a pull 20 which is substantially at the middle of the traveler, so that the wear thereon is equalized at the two points of contact between the traveler and ring flange.

30 The inward extension of the flange 14 permits the use of larger spinning rings and hence of larger bobbins without diminishing the necessary space between adjacent rings, which is a decided advantage, and in a large mill where thousands of spindles are in use results in a very decided economy by increasing the output each day, as compared with former constructions of rail. To give a concrete example it has been found by experiment that where the flanges 14 are extended inwardly to agree with the inner edges of the rings a two and one-quarter inch ring may be placed on the rail with the same space between bobbins as would be required for a two inch ring where the overhanging flange 14 was disposed as shown in my prior patent. Assuming that the necessary space between rings is as shown in said patent where the flanges 18 are coincident substantially with the outer diameter of the ring, by reconstructing the rail and strip so as to accommodate a two and one-half inch ring, a ring of such increased diameter could be used by having the flange agree with the inner circle of the ring, and without altering the amount of space between adjacent rings.

40 Other advantages and benefits of the invention will be apparent to those skilled in

the art without further elaboration thereof.

I claim:

1. A thread guard comprising in combination with a spinning ring rail, an overhanging projecting flange arranged above the spinning ring and extending partly but not wholly around the circumference of said ring, the extreme inner edge of said flange being substantially in vertical coincidence with the inner edge of the ring for a substantial portion of the distance around the ring. 60

2. In a thread protector for spinning rings, the combination with a ring rail, of a ring thereon and an enclosing guard for the raceway arranged to extend above and to overlap a portion of the ring, the inner edge 70 of the overlapping part of the guard arranged in substantial coincidence with the inner edge of that portion of the ring above which said guard is located. 75

3. In a thread protector for spinning rings, the combination with a ring rail, of a ring thereon, an enclosing means arranged to extend around at least one-half of the circumference of the ring, and shaped to overlap the ring flange, said enclosing means having its extreme inner edge extending at least as far over the ring as the inner circumference thereof. 80

4. In a device of the class described, the combination with a spinning frame, having a plurality of openings, a plurality of spinning rings above said openings, a plurality of enclosing devices on said frame each extending a substantial distance around a ring and having a flange overlapping the ring flange and in vertical alignment at its inner edge with the inner edge of the ring flange for that portion of the ring which is overlapped by the enclosing device. 90

5. In a device of the class described, the combination of a ring rail having a plurality of openings therein, rings arranged above said openings, a strip supported by said rail and provided with recesses for receiving said rings, the recesses partly surrounding the 100 rings and being open at their front portions, and flanges overlying said recesses and said rings, the inner edges of said flanges overlapping the rings for at least one-half of their circumference, the inner edges of said flanges being coincident vertically with the extreme inner edges of said rings. 105

In testimony whereof I have hereunto set my hand this 16th day of May, A. D. 1927.

CHARLES D. WHITE.
